Primary Examiner — John R Yeh*(74) Attorney, Agent, or Firm* — Kilpatrick Townsend & Stockton LLP(57) **CLAIM**

The ornamental design for a grill brush pad, as shown and described.

DESCRIPTION

FIG. 1 is a front view showing our new design for a grill brush pad;

FIG. 2 is top view thereof;

FIG. 3 is a bottom view thereof;

FIG. 4 is left side view thereof;

FIG. 5 is a right side view thereof; and,

FIG. 6 is a rear view thereof.

The broken lines depict portions of the grill brush pad that form no part of the claimed design.

1 Claim, 6 Drawing Sheets(56)
